ENGLAND.

ORDNANCE SIGHTING APPARATUS.

1,300,354.

Specification of Letters Patent. Patented Apr. 15, 1919.

Application filed June 21, 1917. Serial No. 176,112.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Ordnance Sighting Apparatus, of which the following is a specification.

This invention relates to sighting apparatus of the kind comprising a sight bracket which is pivotally mounted on the gun cradle for range adjustments and which has a sight carrier pivoted thereto for lateral adjustments. In such apparatus it is usual to employ an arm elevated for range on which the deflection dial and the handle of the deflection gear are carried and to mount the range adjusting gear on a plate or bracket attached to the gun cradle. With such an arrangement the relationship or relative position between the deflection dial and the range dial alters every time a range adjustment is made, although in sighting apparatus of other kinds means have been suggested for preventing such alteration in relationship which is particularly undesirable when the sighting apparatus is designed to give large range adjustments.

According to the present invention we so construct and arrange the deflection gear in sighting apparatus of the kind above set forth, that the deflection dial can be carried by the gun cradle, preferably upon the plate or bracket that carries the range dial. In this manner not only is the relationship between the dials maintained constant, but no trouble is experienced in regard to the overhead decks of a ship or to the roof of a shield when the sights are in the "fool proof" position. By the term fool proof position is meant the position of the telescopes, deflection arms, etc., when maximum range is put on the sight, while the gun itself is registering maximum depression. This of course is not a working position, but the overhead decks and the roof of the shield have to be made to clear such position.

In order that the said invention may be clearly understood and readily carried into effect, we will describe the same more fully

with reference to the accompanying drawings, in which:

Figure 1 is a side elevation showing a form of sighting apparatus constructed in accordance with our invention.

Fig. 2 is a view similar to Fig. 1 but on a smaller scale, showing a modified form of the sighting apparatus with the gun assumed to be at its maximum angle of elevation, and

Fig. 3 is an end elevation of Fig. 2 viewed in the direction of the arrow in the latter figure and drawn to a larger scale, a portion being in section on the line 1, 1 of Fig. 2.

A is the sight bracket or frame and A' the sight carrier. B is the deflection dial and B' the handle of the deflection gear. C is the range dial and C' the handle of the range adjusting gear which in the examples shown comprises a cam C². D is the aforesaid plate or bracket attached to the gun cradle. The said plate carries the dials B and C, the handles B' and C' and the cam C².

In the example shown by Fig. 1 there is provided a toothed bevel arc D^x connected to or made integral with a worm wheel arc D' with which gears a worm b carried by a spindle b' operated by the deflection handle B'. Meshing with the bevel arc D^x is a pinion a carried by a spindle a' mounted in bearings on the sight bracket A and connected by suitable gearing such as a screw and nut with the sight carrier A'. The said bevel arc D^x is mounted co-axially with the pivot of the sight bracket A and owing to the engagement of the aforesaid worm b with the worm wheel arc D', is prevented from moving during the elevation of the sight bracket by the cam C². As the pinion a meshing with the bevel arc D^x is carried by the sight bracket, the elevation of the latter causes the pinion to run on the bevel arc and the sight carrier is thereby automatically deflected for drift. When the deflection handle B' is operated the bevel arc D^x is angularly displaced relatively to the sight bracket and the pinion is thereby rotated to impart the speed of target deflection to the sight carrier A'. The spindle b' is provided with another worm b² for actuating the deflection dial or its pointer.

In the example shown by Figs. 2 and 3 the adjustment for drift is arranged by placing the sight frame A, the plate D attached to the gun cradle and the cam C² on an axis which is called the drift axis, inclined to the gun trunnion axis. When range is put on the sight, the sight frame A is rotated around the drift axis by means of the cam C² operating on the push rod 10 connected to the frame A.

Adjustment for deflection is made through the spindle b' which is connected by bevel pinions to a screw b³ engaging with a nut b⁴ which carries a member B² having a 15 curved slot B³ concentric with the drift axis; the sight carrier A' has an upwardly inclined deflection arm A² carrying a shoe A³ disposed in the said curved slot B³; the sight carrier A' is made to rotate on the 20 deflection pivot by means of the member A² which receives its motion from the member B² moved by means of the nut B⁴ at right angles to the deflection pivot.

During the range adjustment of the sight 25 the shoe A³ slides in the said curved slot B³ and is drawn up and down the slot by the sight frame A so as to obviate any bending action on the arm A²; thus connection is maintained at all times between the deflection gear and the deflection arm A². The latter is connected by a transverse rod a³ 30 to the deflection arm appertaining to the sight on the opposite side of the mounting as shown by Fig. 3.

35 What we claim and desire to secure by Letters Patent of the United States is:—

1. In ordnance sighting apparatus, the 40 combination with the gun cradle of a sight bracket pivotally mounted on the gun cradle for range adjustments, a sight carrier pivoted to the sight bracket for lateral adjustments, range adjusting gear, including a range indicator carried by the gun cradle and deflection adjusting gear, including a 45 deflection indicator also carried by the gun cradle.

2. In ordnance sighting apparatus, the 50 combination with the gun cradle of a sight bracket pivotally mounted on the gun cradle for range adjustments, a sight carrier pivoted to the sight bracket for lateral adjustments, range adjusting gear, including a range indicator and a range setting handle both carried by the gun cradle, and deflection 55 adjusting gear including a deflection indicator and a deflection setting handle both also carried by the gun cradle.

60 3. In ordnance sighting apparatus, the combination with the gun cradle of a sight bracket pivotally mounted on the gun cradle for range adjustments, a sight carrier pivoted to the sight bracket for lateral adjustments, range adjusting gear including a range indicator, deflection adjusting gear 65 including a deflection indicator, and a plate

attached to the gun cradle, the said plate carrying both said indicating devices.

4. In ordnance sighting apparatus, the combination with the gun cradle of a sight bracket pivotally mounted on the gun cradle 70 for range adjustments, a sight carrier pivoted to the sight bracket for lateral adjustments, range adjusting gear, including a range indicator carried by the gun cradle, deflection adjusting gear, including a deflection indicator also carried by the gun cradle, and a member operating to move the sight for deflection adjustments and also for automatic drift adjustments.

5. In ordnance sighting apparatus, the 80 combination with the gun cradle of a sight bracket pivotally mounted on the gun cradle for range adjustments, a sight carrier pivoted to the sight bracket for lateral adjustments, range adjusting gear, including a 85 range indicator carried by the gun cradle, a deflection setting handle and a deflection indicator carried by the gun cradle, a toothed member connected by locking gear 90 ing with the deflection setting handle, means whereby on actuation of said handle the said member imparts deflection to the sight carrier and means whereby during the range adjustment of the sight bracket the said member imparts automatic drift movement 95 to the sight carrier.

6. In ordnance sighting apparatus, the combination with the gun cradle of a sight bracket pivotally mounted on the gun cradle 100 for range adjustments, a sight carrier pivoted to the sight bracket for lateral adjustments, range adjusting gear, including a range indicator carried by the gun cradle, deflection adjusting gear, including a deflection indicator carried by the gun cradle, 105 a deflection setting handle, a member moved laterally by said handle, a second member for transmitting deflection to the sight carrier, this member moving with the sight bracket during range adjustments and a 110 sliding connection between said two members.

7. In ordnance sighting apparatus, the combination with the gun cradle of a sight bracket pivotally mounted on the gun cradle 115 for range adjustments, a sight carrier pivoted to the sight bracket for lateral adjustments, range adjusting gear, including a range indicator carried by the gun cradle, deflection adjusting gear, including a deflection indicator carried by the gun cradle, 120 a deflection setting handle, a curved member moved laterally by said handle and a second member for transmitting deflection to the sight carrier, this member moving with the sight bracket during range adjustments and being slidably engaged with the first mentioned member.

8. In ordnance sighting apparatus, the combination with the gun cradle of a sight 125

bracket pivotally mounted on the gun cradle to move during range adjustments about a drift axis at an angle to the gun trunnion axis, a sight carrier pivoted to the sight bracket for lateral adjustments, range adjusting gear, including a range indicator carried by the gun cradle, deflection adjusting gear, including a deflection indicator carried by the gun cradle, a deflection setting handle, a curved member moved laterally by said handle and a second member for transmitting deflection to the sight carrier, this member moving with the sight bracket during range adjustments and being slidably engaged with the first mentioned member.

10 In testimony whereof we affix our signatures.

ARTHUR TREVOR DAWSON.
GEORGE THOMAS BUCKHAM.
